UNITED STATES PATENT OFFICE.

EDWARD D. MACKINTOSH, OF NEW YORK, N. Y., ASSIGNOR OF ONE-HALF TO S. S. HEPWORTH COMPANY, OF NEW YORK, N. Y., A CORPORATION OF NEW YORK.

CENTRIFUGAL MACHINE.

1,133,811.

Specification of Letters Patent. Patented Mar. 30, 1915.

Application filed April 13, 1911. Serial No. 620,749.

To all whom it may concern:

Be it known that I, EDWARD D. MACKINTOSH, of the borough of Brooklyn, in the city of New York, county of Kings, and State of New York, have invented certain new and useful Improvements in Centrifugal Machines, of which the following is a specification.

My invention relates to improvements in that class of centrifugal machines in which rotation is permitted to take place about an axis not coincident with the axis of the machine, and it is the object of my improvements to facilitate such rotation and to keep its axis stationary and vertical, as nearly as may be.

Referring to the accompanying drawings, forming part of this specification, Figure 1 is a vertical section of my invention and Fig. 2 is a plan of some of the parts shown in Fig. 1.

A shaft 1, adapted to carry the basket of a centrifugal machine at its lower end, is fixed to a pulley 2 driven by a belt 3. A drum 4 is integral with the pulley and is used for stopping the machine by means of any suitable brake. The shaft is supported by a head consisting of a rotor in the form of a sleeve 5 and a grooved spool 6; a stator 30 in the form of grooved rings 7 connected by a casing 8, and balls 9 separating the two while maintaining their relative positions and permitting the rotation of one within the other. The head is swingable 35 with the shaft and rests upon a support which is yieldable to the swinging and which consists of a spherical zone 10 fitting a socket 11 in a hanger 12. A tube 13 retains oil used for lubrication and an opening in the 40 top of the zone 10 permits circulation of the oil.

The support of the head against the pull of the belt 3 is afforded by an abutment consisting of two strips 14, of leather or 45 other suitable material, filling part of the space between the head and the hanger, and

secured to blocks 15 confined in the hanger. When swinging occurs the head rocks on and away from the abutment, leaving it at the top and the bottom alternately, and sliding toward and from it on the yieldable support. The belt meanwhile tends to pull the head back toward the abutment, whenever it rocks on and away from it, and thus urges the machine to verticality.

Having now described my invention, what I claim as new, and desire to secure by Letters Patent, is:

1. In a centrifugal machine adapted to be driven by a belt, a normally vertical swingable shaft, a head supporting the shaft and swingable therewith, and an abutment against which the belt holds the head and on which and away from which the head rocks as the shaft leaves the vertical, the point of contact between the head and the abutment being above the center line of the belt when the shaft swings from the vertical in one direction and below said center line when the swing is from the vertical in the opposite direction.

2. In a centrifugal machine adapted to be driven by a belt, a head having a rotor and a stator separated by balls that maintain the relative positions of the two while permitting the rotation of one within the other, a normally vertical shaft supported by the head and swingable therewith, an abutment against which the belt holds the head and on which and away from which the head rocks as the shaft leaves the vertical, a spherical zone supporting the head, and a socket fitting and supporting the spherical zone.

In testimony whereof I have signed my name to this specification in the presence of two subscribing witnesses.

EDWARD D. MACKINTOSH.
